TRANSFORMER BRACE

Homer Churchill, East Orange, N. J., assignor
to Line Material Company, South Milwaukee,
Wis., a corporation of Delaware

Application November 16, 1934, Serial No. 753,351

2 Claims. (Cl. 248—215)

This invention relates to improvements in transformer braces.

Transformer hangers are frequently provided comprising vertically disposed relatively spaced supporting straps secured to the transformer casings and having hook-shaped upper ends engaging the cross-arms of transmission line poles, the lower end of the straps being engaged by braces or supports which rest against the pole and hold the transformer casing in an upright position.

It is an object of this invention to provide a brace or support for the strap hangers of a transformer casing removably and securely engaging the lower ends of the hangers without bolts or other extra parts, thereby to hold the casing in an upright position and to simplify the operations of hanging a transformer on a pole.

A further object is to provide transformer hangers and braces which will require less operations to manufacture than has heretofore been necessary.

In the drawing

Fig. 1 is a view in side elevation illustrating an embodiment of this invention as applied to a transformer casing when mounted on a pole.

Fig. 2 is a view in side elevation of the device shown in Fig. 1, a portion of the pole being broken away.

Fig. 3 is a sectional view taken on the line 3—3 of Fig. 1.

Fig. 4 is a sectional view similar to Fig. 3 showing a modified form of the invention.

Figs. 5 and 6 are fragmentary sectional views similar to Fig. 3 and illustrating further modified forms of this invention, the views being smaller than Figs. 3 and 4.

Throughout the several views, like parts are identified by the same reference characters.

The transformer casing 1 is provided with a pair of vertically spaced lugs 2 for each of the hanger straps 3 and to which the straps are secured by means of nuts 4 engaging their respective stud bolts 5. The upper ends of the hanger straps 3 converge vertically relative to each other at the portions 6 and terminate at the ends in hooks 7 which extend over the cross-arm 8 on the pole 9. The hooks 7 may be secured to the cross-arm by means of spikes or screws 10. The lower ends of the hanger straps 3 extend below the bottom of the transformer casing 1 and are engaged by a brace or support 11.

The brace or support 11 shown in Figs. 1, 2 and 3, comprises an intermediate arcuate portion 12, relatively parallel portions 13 extending from the ends of the arcuate portion 12, and U-shaped

arms 14 having their open ends disposed outwardly and exteriorly relative to the portions 13 of the brace. As shown, these U-shaped arms receive the lower ends of the hanger straps 3, preferably in frictional engagement therewith. The brace may be secured to the pole 1 by means of a screw bolt 15.

The modified form shown in Fig. 4 is similar to that shown in Fig. 3 except that the arms 14A are bent inwardly to provide the U's having their open ends disposed adjacent the inner faces 16 of the portions 13. The arms 14A in Fig. 4 engage the hanger straps 3 in the same manner as the arms 14 engage the hanger straps illustrated in Fig. 3.

It will be noted that in the braces shown in Figs. 3 and 4 the arms 14—14A are shaped so that the open end of the U's face outwardly relative to each other, whereas in Figs. 5 and 6 the U-shaped arms 17—17A are shaped so that the U's open inwardly relative to each other. The modifications shown in Figs. 5 and 6 operate in the same manner as that described in reference to the forms illustrated in Figs. 3 and 4, but the arcuate portions 18 of the braces are shorter in length than the arcuate portions 12 in Figs. 3 and 4. Thus, a minimum amount of metal is required to manufacture the braces illustrated in Figs. 5 and 6.

In mounting the transformer casing on a pole, the brace 11 may be first secured to the pole and then the transformer casing with the hanger straps secured thereto may be elevated from the ground sufficiently to permit the lower ends of the hanger straps to be inserted in the U-shaped arms of the brace and at the same time to hook the hanger straps on the cross-arm of the pole. If the brace 11 is provided with its U-shaped arms engaging the lower ends of the brackets with sufficient friction to hold them in engagement therewith, they may be mounted on the lower ends of the hanger straps 3 before the transformer casing 1 is mounted on the cross-arm 8 as shown. After the transformer casing has been thus mounted, the brace 11 may be secured to the pole by means of the bolt 15.

It will be noted that no bolts or other means are provided for securing the U-shaped arms of the brace 11 to the hanger straps 3. Heretofore it has been found necessary to secure the lower ends of the hanger straps to the braces in order to prevent the transformer from swaying on the cross-arm of its supporting pole. The bolts usually provided for this purpose serve no other purpose. In the present invention such bolts or securing

means are eliminated and the transformer casing is prevented from swaying because the lower ends of the hanger straps are inserted within the U-shaped arms. Therefore the necessity of other means for holding the transformer casings against swaying is removed.

It will be further noted that the transformer brace made as disclosed in the drawing, requires almost entirely nothing more than bending operations in its manufacture. Obviously, this will materially minimize the cost of manufacturing braces for transformer casings.

I claim:

1. In a transformer hanger a single piece of

strip metal bent to form an arcuate portion, a pair of spaced relatively parallel portions each extending from an end of the arcuate portion, and a pair of U-shaped arms extending angularly from the relatively parallel portions.

5

2. In a transformer hanger having a pair of spaced vertically extending straps, a brace for the lower ends of said straps, said brace comprising a single piece of strip metal having an intermediate arcuate portion and its ends bent to provide substantially parallel portions and U-shaped arms disposed in a common plane and at right angles relative to the parallel portions.

10

HOMER CHURCHILL.
